ROASTING RACK

Donald K. Ferris, Dayton, Ohio

Application July 5, 1947, Serial No. 759,191

2 Claims. (Cl. 99—449)

1

This invention relates to an adjustable rack or grid of the type adapted to support meat roasts and other foods during the cooking process and also to support such foods for carving or cooling after they have been cooked, baked, or otherwise prepared for human consumption.

One of the objects of the invention is to provide a rack or grid device which may be easily adjusted to accommodate roasts, poultry, and the like, of various sizes and weights.

Another object is to provide a roasting rack of the foregoing characteristics wherein the supporting grills may be adjusted to a flat position, thereby to render it usable as a cooling rack for cakes and the like, the construction of the rack permitting a free circulation of air about all surfaces of the articles to be cooled.

A further object of the invention is to provide a roasting and cooling rack which may be easily collapsed into a compact form for storing when not in use.

Another object is to provide a roasting and cooling rack of such simple construction as to render the cleaning thereof an easy task.

Still another object is to provide a roasting and cooling rack of low cost, the component parts thereof being fabricated on punch presses and assembled without the use of welds, screws, rivets, and the like.

These and other objects and advantages are attained by the means described herein and illustrated upon the accompanying drawings, in which:

Fig. 1 is a perspective view of the rack or grid showing the device in one of the positions for supporting a roast or the like.

Fig. 2 is a perspective view showing the device in collapsed position.

Fig. 3 is an end elevational view, partly in cross section, showing the rack in fully extended or flattened position, adapted to be used for cooling cakes and the like.

Fig. 4 is an enlarged fragmental perspective view of a detail of the invention showing the construction of a support grill.

Fig. 5 is an enlarged fragmental perspective view of a base member, showing the method of reinforcing said member.

Fig. 6 is an enlarged fragmental cross sectional view of the base connecting strap, taken on line 6—6 of Fig. 1.

Fig. 7 is an enlarged cross sectional view of a portion of the device, taken on line 7—7 of Fig. 6.

Although there are various types of roasting racks available upon the market, there is a need for a rack which may be manufactured cheaply by mass production methods and sold to the

2

consumer at a low cost. As will presently be shown, the device of the present invention incorporates these advantages. In addition, objectionable limitations of former roasting racks have been eliminated, as will presently be explained.

Referring to the drawing, the device shown in Fig. 1 comprises a pair of base members 9 and 10 which are united in spaced substantial parallelism by a connecting strap 12. The base members 9 and 10 may be substantially U-shaped in cross section, being provided with outwardly extending flanges 13 and 14. Each base member, intermediate its ends and adjacent the lower flange 13, is provided with a slit 16 (Fig. 6), through which the ends 17 of the connecting strap 12 are inserted. The ends 17 protrude sufficiently through the base members 9 and 10 to permit turning said ends under the lower flange 13 of each base member, as indicated in Fig. 6. By forming the ends 17 of lesser width than the main portion 18 of the connecting strap 12, as shown in Fig. 7, the base members 9 and 10 are held in rigid parallelism, since the shoulders 19—19 of the strap 12, by their abutment against the inner faces of the base member vertical web portions 20—20, provide substantial reinforcement against angular movement of said base members. Rigidity may be imparted to the connecting strap 12 by longitudinally crimping its main portion 18 to form an inverted V, as shown in Fig. 3.

The vertical web portion 20 of each base member is provided with a pair of identical inwardly and upwardly inclined slots 21—22, one slot of each pair being the reverse of its mate. These slots serve as runways for the wire loops 23 and 24 laterally extending from the sides of a pair of identical support grills 26 and 27.

As shown in Fig. 1, the support grills 26 and 27 may be formed of sheet metal and provided with a plurality of openings 28 to permit a free circulation of air or heat about the meat to be roasted. To impart rigidity to the support grills, the ribs 29 may be longitudinally crimped, as shown in Figs. 3 and 4. Each end of the support grills 26 and 27 is provided with a tapered flange 30.

As shown in Fig. 4, the large end of each tapered flange is apertured as at 31, to receive the turned-in ends of the heavy wire rod 33, provided at its opposite ends with a hook or loop 24. After insertion through the apertures 31, the ends 32 of the wire are swaged flat or otherwise formed to preclude longitudinal movement of the wire rod 33 in the grill flanges 30. As indicated in Fig. 4, the edge of the flange 30 is notched, as at 34, to receive the wire rod 33.

thereby to preclude pivotal movement of said rod in the apertures 31.

As hereinbefore recited, the inclined slots 21 and 22 serve as runways for the wire loops 23 and 24. It will be noted in Fig. 3, that the slots are provided with a series of notches or serrations 36, 37, and 38, which serve as seats for that portion of the wire loop indicated at 39 in Fig. 4. The grills are thus adjustable to various angular positions. One of the angular positions is shown in Fig. 1, the loop portions 39 being disposed in the notches 38, while the loop portions 40 rest upon the lower smooth edges 41 of the slots 21 and 22, thereby to support the grills in an inclined position. The supporting grills 26 and 27 may be spaced farther apart by engaging the loop portions 39 in any of the remaining notches such as 36 or 37. The inner termini of the slots 21 and 22 are turned upwardly to form the seats 42 for positioning the grill supports 26 and 27 to a substantially closed V formation.

Thus it will be seen that when the loop portions 39 are seated in oppositely mating notches in the base members 9 and 10, the longitudinal axes of the supporting grills 26 and 27 will be substantially parallel. In these positions, the rack is adapted to support roasts of meat during the cooking process, heat being permitted to circulate about all surfaces of the roast by virtue of the openings 28 in the grills. In some cases, it may be desirable to adjust the grills 26 and 27 to a V formation having the longitudinal axes of the grills converging, as when baking a ham or roasting a fowl. In such cases, the loop portions 39, at one end of the grills, are seated in notches toward the outer ends of one base member, while the opposite loop portions 39 are seated in notches toward the center of the opposite base member. For instance, if loop portions 39 are seated in notches 36 of base member 9, and the loop portions 39 at the other end of the grills are seated in notches 38 or 42 of base member 10, the axially converging grills 26 and 27 will be ideally suited to support a ham in a substantially horizontal position.

It will be noted that an enlarged notch 43, between the seats 38 and 42, has been provided in each slot 21 and 22. By disposing the loop portions 39 in the enlarged notches 42, the grills 26 and 27 will assume the fully extended position shown in Fig. 3, wherein the grills are disposed in substantial coplanar relationship with each other, and with the top flanges 14 of the base members 9 and 10. In this position the device is readily adapted for supporting cakes while they are permitted to cool, serving in such function to expose the under surface of the cake to the atmosphere by virtue of the various openings 28 provided in the grills and therebetween.

As shown in Fig. 5, the outer termini of the slots 21 and 22 are turned upwardly and inwardly close to the flanges 14, to form a substantial half circle 44. This semi-circular terminus of the slots permits a pivoting movement of the grills 26 and 27 to the folded or collapsed position shown in Fig. 2. In this position the wire loops 23 and 24 are disposed in the semi-circular track 44, as pictured in Fig. 2. It will be noted that the device in the collapsed or folded position, wherein one grill overlaps the other between the base members 9 and 10, assumes a very compact form, permitting storage in a small space when not in use.

Since the structure of the base members 9 and 10 may be weakened by virtue of the removal of

material in forming the semi-circular track 44, reinforcing means for the vertical web portion 20 of said bases may be provided. In the instant case, an elongated groove 46 is stamped in the base members adjacent the outer ends thereof, as indicated in Fig. 5. Other means for reinforcing the base members 9 and 10 may be employed, such as providing an outwardly turned flange at the ends of said base members.

From the foregoing, it will readily be seen that the device of the present invention lends itself to mass production methods, the principal parts thereof being fabricated upon punch presses from sheet metal. Since there are no welds, rivets, or the like used in the assembly of the device, no skilled labor need be employed in the fabrication of the rack, resulting in substantial savings in the cost of labor.

The device is simple of construction, hence 20 easily cleaned after use and quickly collapsed or folded for storage.

It is to be understood, of course, that various structural changes and modifications may be made within the scope of the appended claims, 25 without departing from the spirit of the invention.

What is claimed is:

1. A roasting rack comprising a pair of similar base members each provided with a pair of elongated similar slots, a substantially smooth lower edge on each slot, spaced seats along the opposite edge of each slot, means connecting the base members in spaced parallelism, a pair of similar grills each comprising an open frame, a lateral extension on each side of each grill, a bearing surface on each extension adapted to selectively engage a seat, and a bearing surface on each extension adapted to rest upon the smooth edge of the slot whereby said grills may be adjustably supported in roast-receiving position, and arcuate outer termini in said slots in which the grill extensions may track in disposing one grill upon the other in overlapping relation to assume a collapsed position.

2. A roasting rack comprising a pair of similar base members each provided with a pair of elongated similar slots, a substantially smooth lower edge on each slot, spaced seats along the opposite edge of each slot, means connecting the base members in spaced parallelism, a pair of similar grills each comprising an open frame, a lateral extension on each side of each grill, a bearing surface on each extension adapted to selectively engage a seat, and a bearing surface on each extension adapted to rest upon the smooth edge of the slot whereby said grills may be adjustably supported in roast-receiving position, arcuate outer termini in said slots in which the grill extensions may track in disposing one grill upon the other in overlapping relation to assume a collapsed position, and inner termini in said slots in which the grill extensions may track to dispose the grills in extended flat relationship without any overlap.

DONALD K. FERRIS.
